SLIP-OVER STYLE OF OUTER GARMENT

Walter A. Riggs, Everett, Wash.

Application October 5, 1946, Serial No. 701,456

4 Claims. (Cl. 2—128)

1

This invention relates to improvements in outer garments, particularly shirts for sport usage, although the invention lends itself equally well to coats, and for its general object aims to provide a slip-over garment which gives extreme freedom for passing the same over the head and yet gives to the wearer the relatively snug neck fit which a dressy appearance demands.

To the above ends, the invention consists in the new design of a slip-over garment having a one-piece front and with the collar of the garment being unattached, from the standpoint of a permanent stitching, to this front part of the garment along one side of the neck, the garment being further characterized in that the frontal edge of one side of an employed yoke piece, and namely the side which corresponds in point of its position to the loose end of the collar, is separably connected to the upper margin of the front, and in consequence of this separation permits the neck opening to be expanded to a very wide compass and thus allowing the shirt to be passed with ease over the head of the wearer.

The invention further consists in the novel construction, combination and adaptation of the parts of the garment, and the garment as a whole, hereinafter described and claimed.

A sport shirt constructed in accordance with the preferred embodiment of the invention is shown in the accompanying drawing, wherein—

Figure 1 is a fragmentary front elevational view confined to that part of the garment, and namely neck and shoulders, with which the present invention is concerned, and illustrating the shirt as it appears in use upon the wearer.

Fig. 2 is likewise a fragmentary front elevational view, but here showing the neck opening as having been widened to the maximum expanse of its permitted enlargement preparatory to donning the shirt; and

Fig. 3 is a view similar to Fig. 2 excepting that the parts are shown as they appear after closing the neck opening and preparatory to turning over the pull-down flap of the collar.

Referring to said drawings, the garment which I have elected to illustrate is a sleeved sport shirt of a collar-attached type, produced from any suitable material and preferably comprised, insofar as the body of the shirt is concerned, of a front, a back, and a yoke, and I designate these parts by the numerals 5, 6, and 7, respectively. The back and the yoke part are or may be fashioned in the usual manner and are connected, also as is customary, by a horizontal line of stitching 8. The front of the garment is of one-

5 piece construction and is formed with a reentrant V-cut placed central to the length of the upper edge, and this V-cut, when the front, back and yoke are together, registers with a complementary reentrant cut placed central to the length of the yoke, the two registering cuts producing the neck opening for the shirt. In sewing the front part 5 to the yoke piece 7, a line of stitching, as 9, runs from one sleeve 10 coextensive of the length of the related shoulder, but from the other side of the neck opening to the other sleeve 11 the said front and yoke are unattached for the greater part of the length to produce a shoulder gap. The resulting free edge 12 of the garment's front part and the oppositely placed free edge 13 of the yoke 7, and, namely, the two edges which describe the margins of the shoulder gap, are each finished with a suitable hem and there is attached to these hemmed edges 15 the usual tooth-carrying webs which form the mating complements of a zipper-type fastening. The two lines of zipper teeth (see Fig. 2) are denoted 14 and 15, and the traveler with its finger-engaged tab which operates to lock and unlock the teeth is designated 16. The application of the zipper to the shoulder opening is such, when the zipper is operated to draw the edges 12 and 13 together and thus close the shoulder opening, that the hemmed frontal margin of the yoke then substantially conceals the zipper, and this is to say that the yoke's frontal edge performs alapping function in respect of the zipper when the latter is closed.

Completing my shirt is a turn-down collar arranged to extend about the opening, and while a major part of this collar is fixedly attached to the body proper of the garment, the garment is peculiarized in that an end of the collar is left free. This free end is the end which traverses 35 the shoulder opening, and its length approximates the length of the free side 18 of the neck's V-cut. The free part of the collar is comprised of two foldably associated wings 20 and 21, the one fold 20 constituting a free prolongation of the collar's attached neck band 22, and the other fold 21 a free prolongation of the collar's attached turn-down flap 23. When the garment is being worn, these two wing folds are adapted one to overlie and the other to underlie the V-cut's free edge 18, and the complements of a snap fastening, as 24 and 25, are affixed to the garment's front part 5 and to the extreme outer end of the wing 20 for detachably securing the one to the other.

When it is desired to don the garment, and

in order that the same may be easily slipped over the head, it becomes necessary only that the wearer disengage the snap element 24 from the snap element 25 and lay the free end of the collar back coincident with the act of unzipping the shoulder gap. After the garment has been passed over the head, the reverse procedure is performed and the garment then has substantially the appearance in which it is illustrated in Fig. 1.

It is thought that my improved slip-over garment will be clear from the foregoing. It is pointed out, however, that while I have described my invention in substantially the exact manner in which I now prefer to produce the same, I do not intend to confine myself to this precise construction. It is believed to be quite obvious that some variation may be made, and I therefore intend that the claims shall be read with only such limitations as are expressly introduced thereto to distinguish the present invention from prior knowledge in the art.

What I claim is:

1. A shirt of the slip-over type providing a neck opening in the body proper of the garment, and having a pull-down collar attached permanently to the body proper of the shirt through a portion only of the length of the collar and such as to leave one end of the collar free, said free end being comprised of a neck band arranged to underlie and a turned-down flap arranged to overlie the body proper of the shirt along the related margin of the neck opening, said neck band having the plan configuration of an elongated tetragon and being unattached to any part of the shirt other than the flap with said attachment extending only along the long side of the tetragonal figure, one shoulder of the shirt having a closeable gap leading laterally as a reentrant slit from the neck opening and originating at a point approximately coinciding with the juncture of the free with the attached portions of the collar.

2. A shirt of the slip-over type providing a neck opening in the body proper of the garment, and having a pull-down collar attached permanently to the body proper of the shirt through a portion only of the length of the collar and such as to leave one end of the collar free, said free end being comprised of a neck band arranged to underlie and a turn-down flap arranged to overlie the body proper of the shirt along the related margin of the neck opening, said neck band having the plan configuration of an elongated tetragon and being unattached to any part of the shirt other than the flap with said attachment extending only along the long side of the tetragonal figure and with the angle which lies between said attached side and the outermost end edge being obtuse, one shoulder of the shirt having a closeable gap leading laterally as a reentrant slit from the neck opening and originating at a point approximately coinciding with the juncture of the free with the attached portions of the collar.

3. A shirt of the slip-over type providing

meeting waist and shoulder-yoking sections acting together to provide a neck opening, and having a pull-down collar for the neck opening permanently attached through only a portion of the length of the collar leaving an end free, said free end being comprised of a neck band arranged to underlie and a turn-down flap arranged to overlie the related margin of the neck opening, said neck-band part of the collar's free portion having the plan configuration of an elongated tetragon and being unattached to any part of the shirt other than the flap with said attachment extending only along the long side of the tetragonal figure, the shirt being formed to present a closeable gap leading laterally as a reentrant slit from the neck opening and originating at a point approximately coinciding with the juncture of the free with the attached portion of the collar, and fastening devices for closing the gap provided along the meeting edges of the latter, one of the two meeting edges which produce said shoulder gap presenting a flap arranged, when said fastening devices are fastened, to project as a fly over and beyond the fastening device for concealing the fastening devices.

4. A shirt of the slip-over type providing meeting waist and shoulder-yoking sections acting together to provide a neck opening, and having a pull-down collar attached permanently to the body proper of the shirt through only a portion of the length of the collar leaving an end free, said free end being comprised of a neck band arranged to underlie and a turn-down flap arranged to overlie the related margin of the neck opening, the shirt being formed to present a closeable gap leading laterally as a reentrant slit from the neck opening and having the components of a zipper fastening provided along the meeting edges of said closeable gap arranged, when zipped for closing, to work in the direction of the neck opening, and also providing a flap arranged, when said zipper is zipped into closed condition, to project as a fly over and beyond the closed zipper to substantially conceal both components of said zipper fastening, said closeable gap originating at a point approximately coinciding with the juncture of the free with the attached portion of the collar and extending along a line parallel, or approximately parallel, with the crest of the garment's shoulder.
